UNITED STATES PATENT OFFICE.

ADOLPH F. GALL AND NATHAN A. CURTISS, OF WEST ORANGE, NEW JERSEY, ASSIGNEES TO NEW JERSEY PATENT COMPANY, OF WEST ORANGE, NEW JERSEY, A CORPORATION OF NEW JERSEY.

MOVING-PICTURE MACHINE.

1,242,792.

Specification of Letters Patent.

Patented Oct. 9, 1917.

Application filed February 24, 1914. Serial No. 820,495.

To all whom it may concern:

Be it known that we, ADOLPH F. GALL, a citizen of the United States, and a resident of West Orange, in the county of Essex and State of New Jersey, and NATHAN A. CURTISS, a citizen of the United States, and a resident of West Orange, Essex county, and State of New Jersey, have invented certain new and useful Improvements in Moving-Picture Machines, of which the following is a description.

Our invention relates to moving picture machines, and more particularly to the means for maintaining a film in a flat and even condition while being fed past exposure position in such a machine.

The principal objects of our invention reside in the provision, in a motion picture machine, of an improved arrangement and construction of the film gate and improved means for opening and closing the film gate, and for locking the latter in closed position.

Another object of our invention is to provide improved film engaging and guiding means, whereby the pressure on the film adjacent the projection aperture of a motion picture machine can be readily and accurately regulated, so that the film will be engaged with just sufficient force to prevent wrinkling or buckling thereof, without substantially hindering or retarding its movement through the machine to bring the pictures successively into registration with the projection aperture.

Other objects and features of our invention consist in the combinations of elements and details of construction hereinafter more fully described and claimed.

For a clearer understanding of our invention, attention is directed to the drawing accompanying and forming a part of this specification, and in which—

Figure 1 is a side elevational view, partly in section, of a portion of a moving picture machine embodying our invention, the plane of section being indicated by line 1—1 of Fig. 2, with the film gate shown in closed position;

Fig. 2 is a sectional view thereof on the line 2—2 on Fig. 1, the film being omitted in this view;

Fig. 3 is a fragmental side elevation view, partly in section, showing the positions of the parts with the film gate in open position;

Fig. 4 is a horizontal sectional view with parts shown in full, taken approximately on line 4—4 of Fig. 1; and

Fig. 5 is a rear elevational view of the aperture plate attached to the frame work of the machine showing the manner in which the wearing strips are mounted.

In the drawing, corresponding parts are designated by the same reference characters throughout the several views.

Referring now to the drawing, reference character 1 indicates a portion of the main frame of a moving picture machine, one side of which frame is provided with a pair of spaced projections 2 extending outwardly therefrom substantially at right angles thereto. A plate 3 provided with the usual projection aperture 3' is removably mounted on the projections 2 in any suitable manner, but preferably by means of bolts 4 and nuts 5, the bolts being rigidly secured at one end to the plate and passing through the projections 2, and the nuts 5 being threaded on the other end of the bolts, as clearly shown in Fig. 1.

Secured to the opposite vertical edges of the plate 3 are wearing strips 6, against which the film 7 is adapted to be pressed, these strips being designed to engage the film only at its edge portions and hold the portion thereof provided with the pictures out of contact with the plate 3. On the strips 6 are guide bars 8, and both the strips and the guide bars are secured to the frame by the screws 9, the strips 6 being provided with open-ended recesses or slots 10 receiving the shanks of the screws, whereby when the latter are loosened the strips may be readily removed and replaced if they become worn. The guide bars 8, as shown in

Fig. 4 are secured to the strips 6 in such a way that the latter are exposed between the inner edges of the guide bars and form therewith a channel of substantially the same width as the film 7 which moves between the guide bars 8 in contact with the exposed portions of the strips 6. As will appear from an inspection of Figs. 1 and 3,

the upper ends 11 of the strips 6 are curved away from the path of the film 7 to prevent the latter from contacting and thereby being scratched or otherwise marred by the 5 upper edge thereof.

Reference character 12 represents the film gate or door which is slidably mounted on a pair of parallel horizontal rods 13 for movement toward and away from the aperture plate 3, as by means of bearings 14 which slidably engage these rods and are secured to one side of the gate, being preferably formed integrally therewith. Rods 13 are fixedly mounted in the frame 1 and extend substantially at right angles to the aperture plate 3 whereby the film gate will always be substantially parallel to the aperture plate. The film gate 12 is provided with the usual large opening 15 registering with the exposure aperture 3'. The front face of the film gate is provided at each side with a pair of vertically alined recessed lugs 16 in the recesses of which are loosely mounted spring-pressed presser bars 17. The lugs 16 at the opposite sides of the film gate are so located and spaced that, when the gate is closed, the presser bars 17 are adapted to engage the outer edge portions of the film 7 between the guide bars 8, and press such portions flatly against the wearing strips 6, as shown in Fig. 4, whereby the film will be maintained in a flat even condition as it passes the aperture plate 3. The bars 17 are engaged by transversely extending spring strips 18 arranged near the top and bottom of the bars and preferably between the upper and lower lugs 16, which springs constantly tend to force the bars away from the gate 12. The strips 18 are engaged substantially at the middle thereof by screws 19 mounted in the gate 12 and by adjusting these screws the bars 17 can be caused to exert a greater or less pressure on the film when the gate is closed. The bars 45 17 are prevented from moving entirely out of engagement with the recessed lugs 16 when the film gate 12 is moved to or is in open position by means of headed bolts 20 which pass loosely through the film gate and 50 are threaded into the bars 17.

To slide the gate 12 on rods 13 into either closed or open position we employ a lever 21 having a slot 22 which engages a bolt 23 secured to the gate. This lever is pivotally mounted near its upper end on a stud 24 secured to the frame 1 and beyond this stud is connected by means of a link 25 to one arm of a bell-crank lever 26, to the other arm of which is secured a handle 27. The 55 link 25 is pivotally connected both to the bell crank lever 26 and to the lever 21, and the bell crank lever is pivotally mounted on a stud 28 secured to the frame 1. By pulling down on the handle 27 the gate 12 is 60 moved away from the aperture plate 3 to

open position, as shown in Fig. 3; and by pushing up on this handle the gate 12 is moved forward into closed position to press the film 7 against the strips 6 as shown in Fig. 1. In either case the film gate slides 70 easily along the rods 13. It will be noted, by reference to Fig. 1, that when the handle 27 is pushed upward it will finally engage a bearing 29, formed at one end of an arm 30 and by means of which the latter is pivotally mounted on a stud 31 secured to the frame 1, whereby the upward movement of the handle is limited. The bell-crank lever 26 and the link 25, pivotally connected thereto and to the lever 21, form a toggle- 75 joint and as the handle 27 is moved upwardly to close the film gate, the pivotal connection between the right hand end of the link 25 and the bell-crank lever 26 will be moved above the line joining the axes of the stud 28 and the pivotal connection between the lever 21 and link 25, and the toggle-joint will lock the film gate and the parts connected therewith in the position shown 80 in Fig. 1. The toggle-joint acts to both lock the film gate 12 in closed or film engaging position and to carry the weight of the handle 27; so that after the handle is moved up into engagement with the hub 29 of the arm 30, as shown in Fig. 1, it may fall back 85 slightly out of contact with this hub, but still be kept by the toggle-joint in its upper position.

Reference character 31 represents one of the film-operating sprockets carried by a shaft or spindle 32 mounted in the frame 1 and which is preferably constructed and connected to its spindle as disclosed in an application of Adolph F. Gall, Serial No. 814,226, filed January 24, 1914, and entitled 105 Moving picture machines whereby a bight or loop may be readily formed in the film between the sprocket and the aperture plate 3, and whereby such loop may be readily replenished when necessary. The arm 30 is provided at its free end with a roller 33 and is acted upon by a spring (not shown) to force the roller toward the sprocket 31 and hold the film in engagement with the latter. Guide rollers 34 for the film are mounted 110 in frame 1 at a slight distance above and below the aperture plate 3 to properly guide the film to and from the latter. The upper end of the gate 12 is provided with a pair of spaced lugs or bars 35 in which is pivotally mounted an arm 36 carrying at its upper end guide rollers 37, adapted when the gate is closed to coöperate with the upper guide roller 34 and hold the film against the latter. The arm 36 is acted upon by a spring 38 115 constantly tending to force the arm and its rollers 36 forwardly toward the position shown in Fig. 3. The arm 36 is provided at its lower end with a projection 39 adapted to coöperate with the upper end of gate 12 120

to limit the forward movement of the arm with respect thereto. The aperture plate 3, the film gate 12, and its operating mechanism, the film operating sprocket 31, the 5 rollers 33, and the guide rollers 34, as well as the other film-operating sprockets and guide rollers (not shown), project outwardly from or are located beyond one side of the main supporting frame 1, whereby, upon 10 opening the film gate and moving the rollers coöperating with the film-operating sprockets away from the latter, the film may be quickly and easily slipped edgewise or side- wise into operative position in the machine. 15 The necessity of threading the film through the machine which is slow and tedious is thus obviated.

From the construction as above described, the mode of operation and utility of our invention will be readily perceived. When it is desired to operate the machine to exhibit moving pictures, the handle 27 is pulled down to open the gate 12 and the arms carrying the rollers coöperating with the film- feeding sprockets, such as 31, are moved away from the latter and the front end portion of the film is then inserted edgewise into operative position as above described, in contact with the aperture plate 3 and 25 guide rollers 34 and in engagement with the teeth of the film- feeding sprockets. The arms carrying the rollers, coöperating with the film- feeding sprockets are now moved into coöperating relation with the 30 latter to maintain the film in operative engagement therewith and the handle 27 is moved upwardly to the position shown in Fig. 1 to close the gate 12 and lock the same in closed position as hereinbefore described. 35 When the film gate is closed the presser bars 17 carried thereby are brought into engagement with the edge portions of the film and press the same against the wearing strips 6 with sufficient firmness to prevent wrinkling 40 or buckling of the film. The pressure of the bars 17 on the film is not, however, so great as to substantially interfere with the feeding movement thereof across the aperture plate 3. The rollers 37 carried by 45 the spring pressed arm 36 on the gate 12 now hold the film in engagement with the upper roller 34 and prevent the film from flapping at the upper end of the aperture plate. As stated above the pressure of the 50 springs 18 on the bars 17 can be varied by the screws 19, and access to the film adjacent the plate 3 can be had at any time pulling the handle 25 downwardly and moving the gate 12 to open position as shown in 55 Fig. 3. All of the parts of the device are easily accessible and in case of wear or accident they can readily be repaired or replaced.

We desire the above description and accompanying drawings to be understood as

being illustrative only as they disclose but a preferred embodiment of our invention, and many changes in the shape, size and arrangement of the parts comprising such embodiment, may be made without any departure from the spirit of our invention and the scope of the appended claims.

Having now described our invention what we claim and desire to protect by United States Letters Patent is as follows:

1. In a moving picture machine, a movably mounted film gate, and unitary means operable by a single manipulation to positively move said gate to either open or closed position and to lock the same in one 80 of such positions, substantially as described.

2. In a moving picture machine, a film gate, and unitary means operable by a single manipulation to either open or close said gate and to positively lock the same in 85 closed position, substantially as described.

3. In a moving picture machine, a film gate, and means including a toggle joint for opening and closing said gate and for locking the same in closed position, sub- 90 substantially as described.

4. In a moving picture machine, a movably mounted film gate, and means including a toggle joint for moving said gate to open and closed position and for locking the 95 gate in one of such positions, substantially as described.

5. In a moving picture machine, a plate having a projection aperture, wearing strips removably secured to said plate on each side of said aperture, and guide strips removably secured to said plate over the wearing strips and exposing portions of said wearing strips between them, whereby a channel is formed through which a film can be moved 100 with its longitudinal edge portions in contact with the wearing strips, substantially as described.

6. In a moving picture machine having an aperture plate, the combination of movably mounted means for pressing the film flatly against said plate, and unitary means operable by a single manipulation to actuate said movably mounted means and to automatically and positively lock the same in 105 film-pressing position, substantially as described.

7. In a moving picture machine having an aperture plate, a film gate having means to engage the longitudinal edge portions 120 of the film and press the same against said plate, rods on which said gate is slidably mounted, whereby the latter can be moved toward and from the film, and manually operable means including a toggle joint for 125 operating the gate and for locking the gate in film-pressing position, substantially as described.

8. In a moving picture machine having an aperture plate, the combination of a device 130

for pressing a film flat against said plate, means for positively moving said device both toward and from the film, and mechanism comprising an essential part of said 5 means for automatically locking said device against the film when moved into engagement therewith, substantially as described.

9. In a moving picture machine, a mov-
10 ably mounted film gate, and means compris-

ing a toggle joint for operating said gate and locking the same in a predetermined position, substantially as described.

This specification signed and witnessed
this 20th day of February, 1914.
